UNITED STATES PATENT OFFICE.

THOMAS MORTON, OF RUTHergLEN, SCOTLAND.

INTERNAL-COMBUSTION ENGINE.

1,384,846.

Specification of Letters Patent. Patented July 19, 1921.

Application filed February 20, 1920. Serial No. 360,023.

To all whom it may concern:

Be it known that I, THOMAS MORTON, Stonelaw Tower, Rutherglen, Lanarkshire, Scotland, a subject of the King of Great Britain, have invented certain new and useful Improvements in Internal-Combustion Engines, of which the following is a specification.

This invention relates to internal combustion engines or motors and its object is to provide an improved lubricating arrangement therefor. The invention relates particularly to such engines or motors as have the crank shaft, connecting rods, and other parts moving inside an inclosed crank chamber and in which the lubrication of the moving parts depends to a great extent on the splashing of oil inside the crank chamber.

In engines of the kind referred to it has been proposed to divide or partition the crank chamber into a series of compartments and to lead the splashed oil from one compartment to the next by inclined channels, finally returning the oil from the last compartment back to the first by an inclined channel or by a pump.

Under this invention the oil, which is splashed up at one end of the crank chamber, is caused to flow directly to the other end thereof and, during its passage, it is cooled by a contra-flow of water.

In carrying out the invention, I provide an oil duct and an adjacent water duct or jacket extending from one end of the crank chamber to the other, the oil duct, at each end thereof, communicating with the interior of the crank chamber. The arrangement is such that the oil, splashed up at one end of the chamber, enters the oil duct and flows down along the same to the other end where it again enters the chamber at a lower level, the oil, in its passage along the oil duct, being cooled by water flowing in a contrary direction through the adjacent water duct or jacket. The water may be circulated by means of a pump and it may also be utilized for cooling the engine cylinders.

If so desired instead of the cooling water flowing in an opposite direction to the oil it may be arranged to flow in the same direction but generally I prefer to use a contra-flow.

The arrangement may be such as to provide for oil circulation and for cooling at both sides of the crank chamber.

Preferably the crank chamber is divided or partitioned, in the known manner, by means of cross ribs, into a series of oil collecting spaces or compartments and the oil, while being circulated and cooled in accordance with my invention, is made to overflow the ribs which determine the level of the oil in the different compartments.

In order that the invention may be clearly understood I have hereunto appended explanatory drawings showing a suitable construction by way of example.

Figure 1 is a side elevation of the bottom part of the crank case of an internal combustion engine of the marine type.

Fig. 2 is a view looking at end H, Fig. 1.

Fig. 3 is a view looking at end G, Fig. 1.

Fig. 4 is a cross section on the line C—D.

Fig. 5 is a cross section on the line A—B.

Fig. 6 is a cross section on the line E—F.

Fig. 7 is a plan of part of the crank chamber.

Referring to the drawings:

The crank chamber *a*, of which the bottom part only is shown, is made, at one end thereof, with an outlet port *b* which communicates, by passages *c*, *c*¹, extending the length of the chamber, with an inlet port *d* at the other end of the crank chamber and at the bottom thereof. At the side of the crank chamber is a jacket *e* which may be provided with a removable cover *f* and cold water is admitted to this jacket by inlet *g* and passes outward by the outlet *h*. In the marine type motor the cold water is drawn in from the sea, by a pump as usual, and then, after passing through the jacket *e*, is delivered to the usual cooling jackets of the engine cylinders.

The bottom of the crank chamber is preferably provided with cross ribs *i* which subdivide the bottom into a series of shallow oil collecting spaces.

k is a filling hole for lubricant.

The arrangement is such that the oil splashed up at the end *G* of the chamber *a* enters the outlet port *b* and flows down the passage *c*¹ and along the duct *c* to the other end of the chamber which it again enters at the inlet *d*. The oil entering at *d* flows into the collecting spaces and overflows the ribs and is then again splashed upward to the outlet *b* and, in this manner, a constant circulation is maintained.

The water passing through the jacket

effectively cools the oil as it passes along the duct *c* and also aids in cooling the oil in the bottom of the crank chamber.

It is obvious that instead of splashing up the oil to the outlet *b* it may be raised thereto by other means than the crank action.

With the improved arrangement as herein described while obtaining an efficient circulation of the lubricating oil and insuring its proper distribution to the several moving parts working within the crank chamber, I am able to maintain the lubricant in cool condition which is also a great advantage. Furthermore, as will now be understood, I secure these advantages without adding materially to the weight of the engine and without making the crank chamber of a complicated or intricate construction.

Having now fully described my invention what I claim and desire to secure by Letters Patent is:—

1. A combined crank chamber and lubricating oil receptacle for internal combustion engines having, in combination, an oil duct in the wall of the chamber and through which the oil is caused to flow, said duct communicating for this purpose with the interior of the chamber at each end, and means whereby the oil, while passing along the duct, can be cooled by a flow of liquid.
2. A combined crank chamber and lubricating oil receptacle for internal combustion engines having integral therewith an oil duct extending from one end of the chamber to the other end and through which the oil is caused to flow, said duct communicating for this purpose with the interior of the chamber at each end, and an adjacent duct through which cooling liquid can be caused to flow to cool the oil in its passage through the oil duct.
3. A combined crank chamber and lubri-

cating oil receptacle for internal combustion engines having, in combination, an oil duct extending in the side wall of the chamber from one end thereof to the other end, said duct being formed for this purpose with a high level entrance at its one end and a low level outlet at its other end both communicating with the interior of the chamber and a jacket located adjacent to the oil duct and through which cooling liquid can be caused to flow to cool the oil in its passage along the oil duct. 45

4. A combined crank chamber and lubricating oil receptacle for internal combustion engines having, in combination, an oil duct in the side wall of the chamber extending from one end to the other end thereof and through which the oil in the chamber can be made to flow, an adjacent jacket open at the side through which cooling liquid can be caused to flow in a contrary direction to the flow of oil, and removable means for closing said jacket. 50

5. A combined crank chamber and lubricating oil receptacle for internal combustion engines having, in combination, an oil duct extending from one end of the crank chamber to the other end and through which the oil forced up at one end of the chamber is caused to flow, said duct communicating for this purpose with the interior of the crank chamber at each end, means whereby the oil, while passing along the oil duct, can be cooled by a contra-flow of cooling liquid, and cross ribs dividing the interior of the chamber into a series of oil collecting spaces. 75

In testimony whereof I affix my signature in presence of two witnesses.

THOS. MORTON.
